(57) **CLAIM**

The ornamental design for a liquid and steam separator, as shown and described.

DESCRIPTION

The file of this patent contains at least one drawing executed in color. Copies of this patent with color drawings will be provided by the Office upon request and payment of the necessary fee.

FIG. 1 is a front view of the liquid and steam separator showing my new design;
FIG. 2 is a front perspective view thereof;
FIG. 3 is an enlarged top plan view thereof;
FIG. 4 is an enlarged bottom plan view thereof;
FIG. 5 is a front view of a further embodiment of the liquid and steam separator showing my new design;
FIG. 6 is a front perspective view thereof;
FIG. 7 is an enlarged top plan view thereof;
FIG. 8 is an enlarged bottom plan view thereof;
FIG. 9 is a front view of a further embodiment of the liquid and steam separator showing my new design;
FIG. 10 is a front perspective view thereof;
FIG. 11 is an enlarged top plan view thereof;
FIG. 12 is an enlarged bottom plan view thereof;
FIG. 13 is a front view of a further embodiment of the liquid and steam separator showing my new design;
FIG. 14 is a front perspective view thereof;
FIG. 15 is an enlarged top plan view thereof;
FIG. 16 is an enlarged bottom plan view thereof;
FIG. 17 is a front view of a further embodiment of the liquid and steam separator showing my new design;
FIG. 18 is a front perspective view thereof;
FIG. 19 is an enlarged top plan view thereof; and,
FIG. 20 is an enlarged bottom view thereof.
